UNITED STATES PATENT OFFICE.

ABRAHAM M. SOUTHARD, OF DENVER, COLORADO, ASSIGNOR TO CHARLES W. PRATT, OF SAME PLACE.

ROCK-DRILL.

SPECIFICATION forming part of Letters Patent No. 659,185, dated October 2, 1900.

Application filed April 22, 1898. Serial No. 678,483. (No model.)

To all whom it may concern:

Be it known that I, ABRAHAM M. SOUTHARD, a citizen of the United States of America, residing at Denver, in the county of Arapahoe and State of Colorado, have invented certain new and useful Improvements in Rock-Drills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in rock-drills of the class set forth in Letters Patent No. 585,795, issued to me July 6, 1897.

My present invention consists of certain improvements on the construction set forth in the aforesaid patent, as hereinafter described and claimed, all of which will be fully understood by reference to the accompanying drawings, in which is illustrated an embodiment thereof.

In the drawings, Figure 1 is a longitudinal section taken through the mechanism on the line *xx*, Fig. 4, looking upward. Fig. 2 is a detail showing the clamp-releasing mechanism in elevation on a larger scale. Fig. 3 is a section taken on the line *yy*, Fig. 2. Fig. 4 is a section taken on the line *ww*, Fig. 1. Fig. 5 is a fragmentary side elevation of the mechanism shown in Fig. 4. Fig. 6 is a section taken on the line *vv*, Fig. 1, looking toward the right. Fig. 7 is a section taken on the line *ss*, Fig. 1, looking toward the left. Fig. 8 is a perspective view illustrating the clamp-releasing jaws separated. Fig. 9 is a top view showing the clamp-releasing jaws connected. Fig. 10 is an underneath view of the same. Fig. 11 is a fragmentary section illustrating the mechanism for regulating the tension of the power-spring and also the mechanism for rotating the drill-shaft. Fig. 12 is a cross-section taken on the line *AA*, Fig. 11. Fig. 13 is a section taken on the line *BB*, Fig. 11. Fig. 14 is a fragmentary perspective view of one of the rods provided with the bevel-faced tongues. Fig. 15 is a section taken on the line *CC*, Fig. 11. Fig. 16 is a fragmentary perspective view of one of the rods provided with the bevel-faced tongues. Fig. 17 is a fragmentary perspective view of one of the rods provided with the bevel-faced tongues. Fig. 18 is a fragmentary perspective view of one of the rods provided with the bevel-faced tongues. Fig. 19 is a fragmentary perspective view of one of the rods provided with the bevel-faced tongues. Fig. 20 is a fragmentary perspective view of one of the rods provided with the bevel-faced tongues. Fig. 21 is a fragmentary perspective view of one of the rods provided with the bevel-faced tongues. Fig. 22 is a fragmentary perspective view of one of the rods provided with the bevel-faced tongues. Fig. 23 is a fragmentary perspective view of one of the rods provided with the bevel-faced tongues. Fig. 96 is a fragmentary perspective view of one of the rods provided with the bevel-faced tongues. Fig. 97 is a fragmentary perspective view of one of the rods provided with the bevel-faced tongues. Fig. 98 is a fragmentary perspective view of one of the rods provided with the bevel-faced tongues. Fig. 99 is a fragmentary perspective view of one of the rods provided with the bevel-faced tongues. Fig. 100 is a fragmentary perspective view of one of the rods provided with the bevel-faced tongues.

and 7, provided with openings through which passes the reciprocating drill-shaft 8. Located within the casing 5 and movably supported on opposite sides thereof are two cogged racks, (designated by the reference characters 9 and 9^a, respectively.) These racks are operated by a mutilated gear 10, journaled in the casing and actuated by a hand-lever 12. Mounted on the forward extremity of each rack-bar is a dog 13, carrying an anti-friction-roller 13^a, which engages a locking-disk 15, mounted on the drill-shaft 8. Immediately in the rear of the disk 15 is the clamping mechanism, comprising a collar 16, a plurality of levers 17, a collar 18, a number of segmental shoes 19, and a small plate 20 for each lever. The shoes 19 engage the shaft 8, against which they are forced by the levers 17, whose forward extremities bear against the shoes. The plates 20 are engaged by fulcrum projections formed on the levers near their forward extremities. The rear extremities of the levers 17 are provided with inclined or beveled inner faces, which are engaged by antifriction-rollers 18^a, carried by the collar 18.

The power-spring 21 surrounds the shaft 8 and its forward extremity bears against the collar 18. The opposite extremity of this spring engages a tension-collar 22, having rearwardly-extending flanges, which overlap the adjacent extremities of a pair of dogs 23, fulcrumed at 28 on a sleeve 29, surrounding a toothed shank 26^a, formed integral with a cogged wheel 26, located adjacent to the rear head 6, between which and said wheel are interposed ball-bearings 27, engaging suitable raceways formed in the said parts. The sleeve 29 is slotted to allow the dog extremities to engage the toothed portion of the shank 26^a. The tails of the dogs project into the cam-slots 22^a, formed in the collar 22. The collar 22, as shown in Fig. 6, is connected with the sleeve 29 by a screw 30, which passes through a slot formed in the collar. The object of this slot is to allow the collar a partial rotation, whereby the cam-walls of the slots 22^a act on the tails of the dogs sufficiently to disengage their noses from the teeth of the shank 26^a when it is desired to adjust the tension devices. The noses of the dogs are held normally in engagement

with the teeth of the shank by coil-springs 31, seated in recesses formed in the sleeve 29 and bearing against the dogs forward of the fulcrum. The periphery of the collar 22 is 5 provided with lugs 22^c for convenience in turning. The sleeve 29 is connected with the shank 26^a of the wheel 26 by a screw 32, which projects into a longitudinal groove 33, formed in the shank. This feature permits 10 the longitudinal movement of the tension devices while the cogged wheel and its shank remain stationary. The tension-collar and its attachments may be moved forward or toward the left, referring to Fig. 1, 15 for the purpose of increasing the tension of the spring by inserting an instrument and pressing the collar in the proper direction. This collar may be moved rearwardly for the purpose of reducing the tension of the spring 20 by first giving the collar 22 a partial turn and disengaging the dogs from the teeth of the shank 26^b, as heretofore explained.

To the rear extremity of each cogged rack is attached a rod 25 by means of a bolt 24. 25 This rod protrudes through the rear head of the casing and enters a closed housing 5^a, which conceals the rod from external view. The wheel 26 is splined on the shaft 8, whereby the latter is allowed to move through the 30 wheel longitudinally. The wheel and shaft, however, must rotate together. This rotation is accomplished through the instrumentality of two tongues 25^a and 25^c, having beveled faces A and B, respectively. The 35 tongue 25^a is located forward of the tongue 25^c, and the two tongues are not in line with each other. The beveled extremities of these tongues are separated by a space 25^d. As one of the cogged racks moves forward 40 the face B of the tongue 25^c engages a cog of the gear 26 and imparts a partial rotary movement to the shaft 6. Simultaneously with this action of the tongue 25^c of the one rod is the action of the tongue 25^a of the 45 other rod, whose face A during the backward movement engages a cog of the wheel and co-operates with the face B of the tongue on the other rod in rotating the wheel and the shaft. The rods 25, being arranged on opposite sides of the gear, are so located that the 50 tongue 25^a of the one rod and the tongue 25^c of the other rod co-operate in imparting the necessary partial rotary movement to the drill-shaft.

55 The action of the tongues 25^a and 25^c is substantially the same as set forth in my previous patent, No. 585,795, dated July 6, 1897, and therefore need not be further set forth in detail.

60 The mutilated gear is journaled in the casing and operated by a hand-lever 12, attached to the journal of the gear. This lever may be made to occupy any desired position by means of a clutch composed of two members 65 3 and 4. When each cogged rack reaches its backward limit of movement, a roller 13^c, mounted on the rear extremity of the dog 13,

engages an inclined stop 36, mounted on the casing. This stop causes the dog extremity to move inwardly sufficiently to release the 70 roller 13^a from the locking-disk 15. The recoil of the spring then acts on the clamping mechanism, heretofore described, and drives the shaft 8 forward.

To the inner surface of the front head 7 of 75 the casing is attached a sleeve 37 by means of bolts 38. Between this sleeve and the locking-disk 15 is located a rubber washer 35, which yields sufficiently when it strikes the sleeve 37 to prevent injury to the parts 80 from jar or concussion. When the shaft reaches its forward limit of movement, the power of the spring is practically spent and the pressure on the collar 18 is reduced sufficiently to allow the shaft to feed automatically through the clamping-shoes 19, thus avoiding the necessity of special feed mechanism.

In order to adjust the reciprocating drill-shaft longitudinally in the casing—for instance, to draw it back after it has been fed through the required distance—the clamp-releasing mechanism (illustrated in Figs. 2, 3, 8, 9, and 10) is brought into requisition and will now be described. This mechanism consists of two pairs of jaws 41 and 42 and a forked lever 43 for operating the said jaws. The jaw 41 is connected with the drill-casing by a pin 44, passing through an aperture formed in the rear extremity of the jaw and upon which the latter is pivoted. This jaw 41 is provided with a slot composed of a straight portion 41^a and an angular portion 41^c. The jaw 41 is further provided with a slot 41^d, formed in its forward portion. The jaw 42 occupies a position above the jaw 41, upon which it is adapted to slide. The two jaws are connected by a bolt 45, passing through an opening 42^a, formed in the jaw 42, and the slot 41^d of the jaw 41. The bolt 110 is fastened by a nut and fits the opening 42^a in the jaw 42 and is adapted to slide in the slot 41^d of the jaw 41. The jaw 42 is further provided with a short slot 42^c, formed in its rear portion. This slot 42^c is about equal in 115 length to that of the angular portion 41^c in the slot of the jaw 41. The lever 43 is provided with two arms 43^a. The upper extremity of each of these arms passes through the rearward slots of a pair of jaws 41 and 120 42. Each pair of jaws normally occupies the outward dotted-line position in Fig. 2.

When it is desired to release the drill-shaft 8 from the action of the levers 17 and the shoes 19, the depending arm 43^c of the lever 125 43 is moved forwardly or toward the left, (referring to Fig. 2,) whereby the forked extremities 43^a are thrust rearwardly or in the opposite direction. As the said arms move toward the rear each engages the inner inclined face of the slot part 41^c and thrusts the two jaws inwardly to the position shown in full lines in Fig. 2. The lever-arm extremity during this movement of the two

jaws travels in the slot 42^c of the jaw 42; but when the inward movement of the jaws is complete—that is to say, when the hooked extremity of the jaw 41 occupies a position 5 to the rear of and engaging the collar 16 and the jaw 42 in front of and engaging the collar 18—the lever-arm extremity reaches the rearward end of the slot 42^c, and as the said lever-arm extremity continues to move in the 10 same direction the jaw 42 is thrust rearwardly, carrying the collar 18 with it, as shown by dotted lines in Fig. 2. During this movement the jaw 42 slides on the jaw 41, the bolt 45 moves in the slot 41^d of the jaw 41, and 15 the lever-arm extremity moves in the straight portion 41^a of the rearward slot in the jaw 41. Hence after the jaw 41 reaches the position shown in full lines in Fig. 2 it holds the collar 16 from movement, while the collar 18 is 20 thrust backward to the dotted-line position. When the collar 18 is in the last-named position, the shoes 19 cease to grip the drill-shaft and the latter may be moved in either direction at will. The lever 43 is fulcrumed 25 on the casing at 43^d, and it is provided with a locking-dog 46, adapted to hold the lever in either position of adjustment. After the drill-shaft has been adjusted as required and it is desired that the clamping mechanism again act upon it the lever 43 is shifted 30 to its original position and the movement of the jaws 41 and 42, as just described, is reversed.

The means for tipping the drill mechanism 35 from the upright position shown in Fig. 4 to the one side or the other, as may be required to permit access to the hole in the rock for the purpose of cleaning it out, will now be described.

To the bottom of the casing is attached a lug 52, which is pivotally connected, as shown at 52^a, with a lug 53, mounted upon a clamp 58, adapted to be attached to a supporting-bar. (Not shown.) To each side of the casing 40 is hinged, as shown at 56, a clamping-plate 54, in which is journaled a set-bolt 55, whose threaded extremity engages a threaded socket formed in the lug 52. The lower extremity of each plate 54 is adapted to engage a beveled or inclined face 53^a, formed on the lug 53. Hence as the set-bolts are 45 screwed into the said openings the plates 54 are made to grip the lug 53 tightly. When it is desired to tip the drill-casing to one side or the other, it is only necessary to unscrew the set-bolt on that side until it is removed from the threaded socket in the lug 52. The plate 54 may then be swung outwardly, whereby it is disengaged from the face 53^a of the 50 lug 53. It is evident that the drill-casing may then be tipped to one side. Each bolt 55 is provided with a head 55^a, fastened to the bolt by a pin 55^c. This head bears against the plate 54 exteriorly. The bolt is provided 55 with a shoulder 55^d, which engages the plate interiorly. Hence the bolt has no longitudinal movement in the plate, but turns freely

therein. This is an essential feature in order that the best results may be obtained from my improved mechanism.

Having thus described my invention, what I claim is—

1. In a rock-drill, the combination with the reciprocating shaft and power-spring, of a clamp comprising a collar surrounding the 75 shaft, shoes located in the collar and engaging the shaft, gripping-levers engaging the shoes, and another collar engaging the levers and against which the power-spring presses, normally causing the lever to grip the shoes 80 whereby the latter are made to grip the drill-shaft.

2. In a rock-drill, the combination with the reciprocating shaft and the power-spring surrounding the shaft, of a collar surrounding 85 the shaft, shoes located in the collar and engaging the shaft, gripping-levers engaging the shoes, another collar engaging the levers and against which the power-spring presses, normally causing the levers to grip the shoes, 90 a clamp-releasing mechanism comprising two connected jaws one being pivoted on the casing, and the other being adapted to slide on the pivoted jaw, and a lever having an arm passing through slots formed in the two jaws, 95 one slot having an angular and a straight portion, and the other slot being shorter, whereby as the lever-arm moves through the angular portion of the one slot, the two jaws are forced inwardly to engage the two collars, after 100 which the lever-arm forces the jaw containing the short slot rearwardly thrusting the collar against the spring, thereby releasing the shaft from the action of the gripping-levers.

3. In a rock-drill, the combination with the drill-shaft and the power-spring surrounding the shaft, of two separated collars surrounding the shaft, one collar being engaged by the power-spring, gripping-levers connecting the 105 two collars, and releasing mechanism comprising two jaws 41 and 42 adapted to hold one collar, while the other is forced rearwardly against the spring and the gripping-levers released, the two jaws being connected by a 110 bolt passing through a slot in the jaw 41 and fitting an opening in the jaw 42, whereby the one jaw is adapted to slide on the other, the jaw 41 being pivoted on the casing and provided with a slot composed of an angular 115 and a straight portion, the jaw 42 being provided with a shorter slot registering with the slot in the jaw 41, a lever having an arm entering the registering slots of the two jaws, whereby they are actuated for the purpose 120 set forth.

4. In a rock-drill, the combination of the reciprocating shaft and the power-spring surrounding the shaft, of a tension-collar surrounding the shaft and engaging the power-spring, a sleeve connected with the collar, the latter being adapted to turn on the sleeve, a dog fulcrumed on the sleeve and having one extremity projecting into a cam-slot

formed in the collar, and a toothed shank splined on the shaft and which the opposite extremity of the dog is adapted to engage.

5. In a rock-drill, the combination of the reciprocating shaft and the power-spring surrounding the shaft, of a tension-collar surrounding the shaft and engaging the power-spring, a sleeve connected with the collar, the latter being adapted to turn on the sleeve, 10 a dog fulcrumed on the sleeve and having one extremity projecting into a cam-slot formed in the collar, and a toothed shank splined on the shaft and which the opposite extremity of the dog is adapted to engage, 15 the sleeve being connected with the shank by a screw passing through the sleeve and engaging a longitudinal groove formed in the shank.
6. The combination with the drill-casing 20 provided with a lug, of a supporting-lug with which the casing-lug is pivotally connected,

a plate hinged to the casing and adapted to engage the supporting-lug, and a set-bolt journaled in the plate and adapted to engage a threaded opening in the casing-lug, for the 25 purpose set forth.

7. The combination with the drill-casing provided with a projection, of supporting means upon which the casing projection is pivotally mounted, a plate hinged to each 30 side of the casing and adapted to engage the supporting means, and a set-bolt journaled in each plate in such a manner as to turn freely, but having no longitudinal movement, said bolt being adapted to engage a threaded 35 opening formed in the casing projection.

In testimony whereof I affix my signature in presence of two witnesses.

Correction in Letters Patent No. 659,185.

It is hereby certified that the name of the assignee in Letters Patent No. 659,185, granted October 2, 1900, upon the application of Abraham M. Southard, of Denver, Colorado, for an improvement in "Rock-Drills," was erroneously written and printed "Charles W. Pratt," whereas said name should have been written and printed *Charles H. Pratt*; and that the said Letters Patent should be read with this correction therein that the same may conform to the record of the case in the Patent Office.

Signed, countersigned, and sealed this 30th day of October, A. D., 1900.
